POCKETBOOK

Philip Wege, West Bend, Wis., assignor to Amity
Leather Products Co., West Bend, Wis.

Application July 12, 1934, Serial No. 734,705

2 Claims. (Cl. 150—42)

This invention appertains to pocket-books of the type generally carried by ladies, and more particularly to pocket-books having a pocket on the inner face of the closure flap thereof for the reception of paper currency and the like. Such a pocket is shown in the Letters Patent to Stemmer No. 1,307,324, granted June 17, 1919. With pockets of this character, entrance to the same is rendered rather difficult, in view of the fact that it is customary to anchor the male section of the snap fastener for the flap to the material forming the cover of the pocket, and to the material forming the flap. Thus the auxiliary flap for the pocket cannot be opened to its fullest extent. Where the stud of the snap fastener is carried solely by the auxiliary flap employed as a closure for the pocket, the auxiliary flap is pulled open by said section of the snap fastener when the main flap is pulled open to permit access to be had to the body portion of the pocket-book. This subjects the contents of the pocket to loss. In order to overcome this difficulty, it has been proposed to lower the pocket a considerable distance inward of its flap, but naturally this also subjects the contents of the pocket to loss.

It is therefore one of the salient features of my invention to provide novel means for securing the stud section of the snap fastener to the main and auxiliary flap in such a manner that the main flap can be readily opened without danger of accidentally opening the auxiliary flap, and whereby the auxiliary flap can be raised to a full open position to permit convenient access to be had to the pocket carried by said main flap.

A further important object of my invention is the provision of novel means for insuring the anchoring of the stud to an adequate number of plies of material, from which the pocket-book is made, whereby tendency of the stud being pulled loose is eliminated, the stud being adapted to project through a suitable opening in the auxiliary flap whereby the stud can conveniently engage the female section of the fastener carried by the body of the pocket-book, and whereby the auxiliary flap can be conveniently swung relative to the male section of the fastener.

A further object of my invention is the provision of means for cutting a portion of the auxiliary flap away from the same, and securing said portion, by sewing or the like, to the main flap, and anchoring the male section of the snap fastener to the material for the flap, and to the material cut away from the auxiliary flap, said means permitting the convenient securing of the male section to the female section of the snap

fastener, and at the same time allowing free swinging movement of the auxiliary flap, the portion of the material cut away from the auxiliary flap forming a complete closure therefor when the auxiliary flap is in its closed position. 5

With these and other objects in view, the invention consists in the novel construction, arrangement, and formation of parts, as will be hereinafter more specifically described, claimed, and illustrated in the accompanying drawing, in 10 which drawing:

Figure 1 is a front elevation of a lady's pocket-book or hand-book, showing the main cover flap thereof in its raised position to permit access to be had to the body portion of the pocket-book, 15 and illustrating the novel means of forming my auxiliary flap for the pocket carried by said main closure flap.

Figure 2 is a view similar to Figure 1 only showing a fragment of the main closure flap, 20 and the auxiliary flap in its open position.

Figure 3 is a detailed sectional view taken on the line 3—3 of Figure 2.

Figure 4 is a view similar to Figure 3, with the auxiliary flap in its closed position. 25

Referring to the drawing in detail, wherein similar reference characters designate corresponding parts throughout the several views, the letter A generally indicates a lady's pocket-book or hand-book constructed in accordance with my 30 invention, and, as shown, the same includes the usual body portion 5, which is generally subdivided into individual compartments for the reception of different articles generally carried by ladies in their bags. The open end of the body 35 5 is normally closed by a main flap 10, and this main flap 10 generally forms a continuation of one side wall of the body portion of the pocket-book. The main closure flap 10 is normally held in its closed position by means of a snap fastener 11, the female portion 12 of which is anchored to the body 5, and the male or stud portion 13 of which is anchored to the main cover flap 10. 40

On the inner face of the main closing flap 10 is arranged a pocket 14 of sufficient depth and length to receive paper currency, or other flat pieces of paper, which may be carried in the pocket-book. As shown, the pocket 14 is made from inner and outer pieces 15 and 16, and these pieces are secured together and to the flap 10 by sewing or the like at transverse edges. The inner edges of the sections 15 and 16 may be integrally secured together, or otherwise fastened by means of stitches or the like. As shown, 45 50 55

the outer section 15 terminates short of the outer or upper edge of the flap 10, and thus the outwardly opening pocket is formed. A pocket 17 is also formed between the flap 10 and the piece of material 15 heretofore mentioned.

An auxiliary flap 18 is carried by the main flap 10, and is provided for the purpose of closing the entrance to the pocket 14. This auxiliary flap 18 extends over the wall 15 of the pocket-book 14, and is detachably connected thereto by the use of a suitable snap fastener 19, one section of which is carried by the wall 15, and the other section of which is carried by the auxiliary flap.

As stated, considerable difficulty is experienced in properly securing the stud 13 of the fastener 11 in place, and at the same time permit convenient opening of the auxiliary flap. Thus, in accordance with my invention, I cut out from the auxiliary flap 18 a central section 20, and rigidly secure the central section 20 to the main flap in any preferred manner, such as by the use of stitching. This forms an enlarged opening 21 in the auxiliary flap.

To the cut-out portion 20, and to the flap, I anchor the male or stud portion 13 of the snap fastener 11, and thus the body portion of the flap 18 is entirely free beyond the fastener which permits the opening of the auxiliary flap to its fullest extent. Obviously, the material 20 rides into the cut-out or opening 21 of the auxiliary flap when the auxiliary flap is in its closed position, and thus in effect seals said cut-out or opening. Naturally the stud or male section 13 of the fastener is always in position for convenient engagement with the female section 12.

From the foregoing description, it can be seen that I have provided a novel and simple means for permitting the free opening movement of auxiliary flaps employed for the pockets of the main closure flaps of women's pocket-books.

Changes in details may be made without departing from the spirit or scope of this invention, but what I claim as new is:—

1. A pocket-book comprising a body, a main closure flap for the body, a pocket carried by the inner face of the flap, an auxiliary flap carried by the first flap for closing the pocket, means for detachably holding the auxiliary flap in a closed position, and means for detachably securing the first-mentioned flap to the body for closing the same, including a snap fastener having one section secured to the body, and the other section secured to the first flap, the auxiliary flap having an enlarged opening therein through which the last-mentioned section of the snap fastener extends, and whereby the auxiliary flap can be swung to a full open position without interference from said last-mentioned section of the snap fastening. 15

2. A pocket-book comprising a body portion, 20 a main closure flap for the body portion, means detachably securing the closure flap over the body including a snap fastener having one section connected to the body and the other section connected to the flap, said flap having a 25 pocket on its inner face, an auxiliary flap carried by the outer edge of the first flap for swinging movement over the open end of the pocket, means securing the auxiliary flap in a closed position over said pocket, said auxiliary flap having a cut-out portion secured to the main flap, the section of the snap fastener carried by the flap being anchored to the material from which the main flap is made, and the material cut out from the auxiliary flap, the position of the last-mentioned section of the snap fastener being such as to permit free engagement thereof with the section carried by the body and to permit free opening movement of the auxiliary flap. 30 35

PHILIP WEGE.
